UNITED STATES PATENT OFFICE.

BRUCE V. EDWARDS, OF NEWARK, NEW JERSEY, ASSIGNOR, BY MESNE ASSIGNMENTS,
TO THE BURCHELL-JOHNSTON CORPORATION, A CORPORATION OF NEW YORK.

THERMOSTATIC APPARATUS.

1,211,116.

Specification of Letters Patent.

Patented Jan. 2, 1917.

Application filed March 28, 1914. Serial No. 827,825.

To all whom it may concern:

Be it known that I, BRUCE V. EDWARDS, a citizen of the United States, residing at Newark, in the county of Essex and State 5 of New Jersey, have invented certain new and useful Improvements in Thermostatic Apparatus, of which the following is a specification, reference being had therein to the accompanying drawing.

10 This invention relates to thermostatic apparatus operating to control an electric circuit for sounding an alarm, operating sprinkler systems or performing other functions, and the invention has special reference to 15 that type of thermostatic apparatus in which the volumetric changes of a fluid body, such as air, due to temperature changes, will operate to control the circuit through the medium of a flexible diaphragm or equivalent 20 member moved by the expansion of the fluid body.

The object of the invention is to produce a device of this character designed more particularly for use in rooms, halls, warehouses and like situations, for indicating the presence of a fire or conflagration, which device will be compact in form, simple in construction, and which while under gradual temperature changes such 30 as climatic changes and those ordinarily occurring in such locations, will not operate to perform its functions, yet will be very sensitive to action under sudden temperature changes, and in such conditions will operate with promptness and certainty in effecting the control of the circuit.

With these objects in view, my invention consists of the improved features of construction and arrangement of the parts particularly set forth in the following description, and the novel features of which are defined in the appended claims.

In the accompanying drawings: Figure 1 is a vertical sectional elevation through the 45 device as it appears when attached for instance to the ceiling of a room; Fig. 2 is a sectional elevation on an enlarged scale of a detail.

Referring particularly to Figs. 1 and 2, 1 50 represents a casing which in the present in-

stance is of hemispherical form, and is preferably of metal of such thickness as to give the proper rigidity, while enabling temperature changes on the exterior to be transmitted to the interior with promptness. This 55 casing constitutes the outer portion of the wall of an air expansion chamber 2, the other portion of which wall consists of an annular plate 3, and a flexible diaphragm A, which latter is shown as covering a central 60 opening in the plate 3. At its outer edge the plate fits closely within the interior of the casing and is sealed therein airtight by any suitable means. At its center the plate is provided with an interiorly threaded opening in which is screwed a sleeve 4 of condensite or vulcanite or similar insulating material. The sleeve is provided with an annular central neck 5 threaded interiorly at its upper portion, in which threaded portion 70 is screwed a nut 6 of brass or other suitable conductive material. Depending from the nut is a stem 6^a which extends downwardly within the neck 5, in which is seated, and suitably insulated therefrom, one of the terminals 7 of an electric circuit, the upper end of which terminal is connected to one of the conductors 7^a of the circuit. The other conductor 8 of the circuit is electrically connected with the nut 6, the stem of which 80 constitutes the other terminal of the circuit, which terminates at its lower end at the level of the terminal 7.

The diaphragm A before alluded to, is sealed at its outer edge around the lower end 85 of the sleeve 4 and presents a surface subject to the expansive action of the air in chamber 2. Resting upon and supported by the diaphragm within the neck 5 is a cup or vessel 9 the upper portion of which is extended downwardly within the body in the form of a collar 10 which loosely surrounds the lower ends of the electric terminals in such manner that the cup will be guided vertically in the up and down movements of 90 the same due to the action of the diaphragm, and will be maintained in an upright position thereon. A quantity of mercury or other suitable conductive material 11 is contained in the cup, the relation and 100

arrangement of the parts being such that under normal conditions, the level of the mercury body will be below the lower extremities of the circuit terminals, but on the rise of the diaphragm due to the expansion of the air in the chamber, the mercury will be carried into contact with the terminals and will effect electric connection between them.

10 The electric circuit in the form of the apparatus shown is normally open, and in the operation of the device, a sudden rise of temperature in the room in which the apparatus is installed, will heat the air body in chamber 2 and will cause the same to expand, and the expanding body of air acting on the diaphragm, will move the same upwardly and this in turn will raise the cup 9 and will bring the body of mercury therein; into contact with the lower ends of the terminals, thereby forming an electric connection between them and closing the circuit.

A vent opening 12 is provided, which in the form of the apparatus shown is formed in the plate 3, the purpose of this opening being to prevent the diaphragm from being moved under the influence of gradual temperature changes due to the ordinary heating of the room or to changing climatic conditions. This opening while restricted, is of such size that in the circumstances mentioned, the air will have time to escape, and therefore will prevent such increase of volume in the chamber as to cause the diaphragm to be moved. In the case of sudden temperature changes however, such as occur from conflagrations, the vent opening, on account of its restricted size, will impede the escape of the air in quantity sufficient to prevent an increase in volume, and consequently the diaphragm will be moved and will carry the mercury body into contact with the terminals.

In order to permit a free movement of the diaphragm under the proper conditions, an opening or openings 13 are formed, preferably in the sleeve 4 through which openings the air within the sleeve may escape, and thus be prevented from interfering with the movement of the diaphragm.

As a means for preventing volatilization or evaporation of the mercury body, I propose to place in the cup 9 on the surface of the mercury, a small quantity 14 of glycerin or like protective substance so as to prevent the air from direct contact with the surface of the mercury. Glycerin when used for this purpose will have the advantage of protecting the ends of the terminals from corrosion or the accumulation of dust or dirt, which would interfere with their conductivity; and it will also act to coat the inner surface of the cup, when the latter is moved about as in transportation, the film

of glycerin thus formed causing the mercury to adhere to the interior walls of the cup and in this way preventing its escape through the collar 10 of the cup.

In the attachment of the apparatus to the ceiling for instance, I propose to employ a block 15 which is adapted to be fastened in place by suitable means. This block contains a central opening 15^a through which the conductors from the terminals pass to the line. Secured to the lower face of the block is a plate 16 provided at opposite sides with oppositely extending key-hole slots 17 adapted to receive headed pins 18 projecting upwardly from the plate 3. In fastening the casing in position, the latter is applied to the under side of the block and the pins 18 entered in the ends of the key-hole slots; whereupon the casing is given a slight circumferential movement so as to interlock the heads of the pins with the edges of the slots.

The conductors of the electric circuit shown may be connected with a suitable device, for instance an alarm bell B but it will be understood that the apparatus is not limited in its application to a signaling device of this type as the conductors may be connected up to operate other devices such as sprinkler systems, and to perform other functions, the invention residing in the construction of the thermostatic controller, without regard to the detailed form of the apparatus operated by the controlled circuit.

In the foregoing description, and in the accompanying drawings, I have shown my invention embodied in the particular forms which I prefer to adopt, but it will be manifest to the skilled mechanic that the details may be variously changed and modified without departing from the limits of the invention; and it will be understood that the invention is not limited to any particular form or construction of the parts except in so far as such limitations are specified in the claims.

Having thus described my invention, what I claim is:

1. In a thermostatic controller having an expansion chamber, the combination of a movable diaphragm, a vessel supported by said diaphragm and having a downwardly and inwardly extending collar, a body of conductive material in said vessel, and an electric terminal extending within the collar in position to be engaged by said conductive body on the movement of the diaphragm.

2. In a thermostatic controller having a fluid expansion chamber the wall of which is provided with an inwardly extending sleeve, the combination of a diaphragm closing the inner end of said sleeve, a neck situated

within the sleeve, thereby forming an annular chamber surrounding the neck and closed at its lower end by the diaphragm, electric circuit terminals extending into the neck, 5 and a vessel containing a liquid body of conductive material, said vessel being sustained by the diaphragm and adapted on the movement of the latter to cause the liquid body to contact with the terminals, said ves-

sel being guided in its movement by the 10 neck.

In testimony whereof I have affixed my signature in presence of two witnesses.

BRUCE V. EDWARDS.
